UNITED STATES PATENT OFFICE

2,056,153

LENS RETAINING DEVICE

Milton J. Belson, Chicago, Ill., assignor to Belson
Manufacturing Co., Chicago, Ill., a corporation
of Illinois

Application September 27, 1935, Serial No. 42,373

1 Claim. (Cl. 240—41.55)

This invention relates to lens retaining devices. It is an object of this invention to provide an improved lens retaining device which is relatively simple and inexpensive in construction and efficient in use.

Another object of the present invention is to provide a new and relatively more efficient device for releasably retaining the lens of an automobile head light lamp, or other lamp, in position of use and in such a manner that the lens may be readily removed and replaced if and when desired.

Other objects will appear hereinafter.

The invention consists in the novel combination and arrangement of parts to be hereinafter described and claimed.

The invention will be best understood by reference to the accompanying drawing showing the preferred form of construction, and in which:

Fig. 1 is a vertical longitudinal sectional view showing a preferred form of the present invention;

Fig. 2 is a transverse sectional view on line 2—2 in Fig. 1;

Fig. 3 is a fragmentary elevational view on line 3—3 in Fig. 2; and

Fig. 4 is a fragmentary top plan view on line 4—4 in Fig. 2.

A preferred form of the present invention as shown in the drawing, is therein generally indicated at 10, and comprises a reflector or lamp housing 11 which has an open end 12, and an end portion 13 which may be attached by means of bayonet slots 14 (Fig. 2), or in any other suitable manner, to a mounting or socket 15, and a conventional lamp bulb 26 is shown mounted in the socket 15 and arranged in the housing 11.

Arranged over the open end 12 of the reflector housing 11 is a transparent or like lens 16 and the present invention is particularly concerned with the provision of a novel means for releasably retaining the lens 16 in position of use upon the reflector housing 11 so that the lens 16 may be readily and quickly removed and replaced as and when desired.

To this end there is provided upon the reflector housing 11, at the open end 12 thereof, a flange or crimped edge 17 which extends around approximately one-half of the peripheral edge or circumference of the housing 11, at the open end 12 thereof, and this flange 17 provides a receptacle for a part of the peripheral edge portion 18 of the lens 16.

Pivottally mounted at its ends, as at 19, upon the reflector housing 11, adjacent the open end

12 of the latter, and adjacent the ends or termini of the flange 17, is a bale or lens-clamping ring 20 which includes a depending flange 21.

Attached to the clamping ring 20, as at 24, is a resilient latch arm 22 and this latch arm 22 includes a clamping portion 23 which is releasably engageable with a latch keeper or stud 25 which is struck up from the surface of the housing 11 (Fig. 1).

Operation

10

The reflector housing 11 may be detachably or otherwise attached to a suitable support such, for example, as the lamp socket 15, and in any suitable manner, as by means of bayonet slots 14 15 or the like.

In order to releasably clamp a transparent or like lens 16 upon the housing 11 the clamping member or bale 20 may be moved into open position (as in dotted lines, Fig. 3), and the lens 16 may be placed against the open end 12 of the reflector housing 11 and above the receptacle or flange 17, (as the parts are seen in Fig. 1), whereupon the lens 16 may be moved in a downward direction, and into the place in which it is shown in Fig. 1, until the lower peripheral edge 25 portion 18 thereof is disposed in the receptacle or flange 17. The clamping member 20 may then be pivoted back into closed or effective position, (from dotted to full line position, Fig. 3), whereupon the resilient latch element or arm 23 30 will engage the latch keeper 25 and retain the clamping member 20 in effective or clamping position, as in Fig. 1; it being noted that when the clamping member 20—21 is in effective or clamping position, (as in Fig. 1, full lines, Fig. 3) 35 the depending flange portion 21 of the clamping member 20 bears against the outer face of the lens 16 and urges the latter into engagement with the wall which defines the open end of the housing 11. In this manner the flange or receptacle 17 and the clamping member 20—21 cooperate to releasably retain the lens 16 in position of use.

If it is desired to remove or replace the lens 16 this may be readily accomplished by unlatching 45 the spring latch element or arm 23 from the latch keeper 25, and then pivoting the clamping member 20—21 into open position (from full to dotted line position, Fig. 3), whereupon the lens 50 may be removed by lifting the same upwardly 50 out of the flange or receptacle 17 and in a plane or direction parallel to the plane in which the lens 16 is shown in Fig. 1.

While I have illustrated and described the pre- 55

ferred form of construction for carrying my invention into effect, this is capable of variation and modification, without departing from the spirit of the invention. I, therefore, do not wish 5 to be limited to the precise details of construction set forth, but desire to avail myself of such variations and modifications as come within the scope of the appended claim.

Having thus described my invention, what I 10 claim as new and desire to protect by Letters Patent is:

A lens-retaining device comprising a lamp housing including a body having an open end and said body being substantially circular in cross 15 section at its said open end, said body including a portion formed integrally therewith and said portion providing a groove substantially channel-shaped in cross section, said groove extending around approximately the lower half portion 20 of the periphery of said housing at the said open end thereof and being disposed radially outwardly from the body of said housing and beyond the outer peripheral surface thereof, said groove providing a receptacle for approximately the lower

half portion of a lens arranged upon said housing at the said open end thereof, a clamping bale including a main body substantially semicircular in cross section and having end portions formed integrally with the said body and lying in a common plane with the latter, said end portions being pivotally mounted directly upon said housing adjacent the said open end thereof and adjacent the upper end portion of said groove, the said body of said clamping bale, when in effective 5 position, projecting only partially, and a relatively short distance, over the said body of said housing from the said open end thereof and less than the entire axial length of said body between the ends thereof, said clamping bale including a 10 portion cooperating with said groove to retain a lens upon said housing whereby the said lens may be inserted into and removed from the said receptacle in a direction transverse to the long axis of said housing, and means for releasably latching 15 the said clamping bale in latched or effective position upon said housing. 20

MILTON J. BELSON.
